INVENTOR

Wallace H. Bate

UNITED STATES PATENT OFFICE.

WALLACE H. BATE, OF BOSTON, ASSIGNOR TO HIMSELF, AND HENRY S. BACON, OF MILFORD, MASSACHUSETTS.

SPRING-SEAT.

SPECIFICATION forming part of Letters Patent No. 288,608, dated November 13, 1883.

Application filed December 9, 1882. (No model.)

To all whom it may concern:

Be it known that I, WALLACE H. BATE, a citizen of the United States, residing at Boston, in the county of Suffolk and State of Massachusetts, have invented an Improvement in Spring-Seats, of which the following is a full, clear, and exact description, reference being had to the accompanying drawings, making part of this specification, in which—

10 Figure 1 is a side elevation of a chair with my improvements applied thereto. Fig. 2 is a vertical section through the center of the same. Fig. 3 is a front elevation.

15 My present invention relates to that class of seats in which springs are employed to enable the same, when occupied, to tilt or incline downward; and my invention consists in a seat pivoted at its front and having one or more springs and a support therefor located 20 under its rear, said seat being disconnected from the back or support, against which the back of the occupant bears, whereby ease and comfort are promoted and the liability of slipping forward avoided, my said invention being adapted for use as a chair, settee, or wag-on-seat.

25 To enable others skilled in the art to understand and use my invention, I will proceed to describe the manner in which I have carried 30 it out.

In the said drawings, A A represent the two front legs; B B, the two rear legs, which are integral with the two respective side pieces forming the back D, the top of the latter sloping to the rear of a vertical plane passing through the tops of the rear legs, and forming 35 an inclined support for the back of the occu-

pant of the chair-seat C, the sides of the front of which or the ends of a cross-bar, a, thereunder are pivoted directly to the tops of the two front legs, A A, no leg-frame being interposed. Under the rear of the seat is located a spring, c, the top of which is secured to the bottom of the seat, and the bottom of the spring resting on a transverse bar, d, which is located upon the upper rungs, e. One spring only is shown; but two or more may be employed when located and arranged in a manner similar to that c—i. e., interposed between the bottom of the seat C and the transverse bar d. The seat has no connection with the back D. When a person occupies a chair of my construction, the weight is brought to bear upon the rear of the seat, which tilts downward against the resistance of the spring or springs c, and when the seat is relieved of pressure it instantly returns to its original horizontal position, a comfortable reclining-chair of simple and economical construction being thereby provided.

I claim—

The combination, with a frame provided with a back, of a seat capable of movement independently of said back, said seat pivoted or hinged at the front of the frame, one or more springs and a support therefor attached to the frame, said support and spring or springs being located under the seat, substantially as and for the purpose set forth.

WALLACE H. BATE.
